UNITED STATES PATENT OFFICE

PERCIVAL ARTHUR BENTLEY, CHARLES FREDERICK MANGER, AND CARLYLE HERBERT WAINWRIGHT, OF LEICESTER, ENGLAND, ASSIGNEES TO THE BENTLEY ENGINEERING COMPANY, OF LEICESTER, ENGLAND, A BRITISH COMPANY COMPOSED OF PERCIVAL ARTHUR BENTLEY AND JOSEPH HOLLAND GODDARD

KNITTING MACHINE

Application filed August 25, 1928, Serial No. 301,983, and in Great Britain August 27, 1927.

This invention is concerned with improvements in or relating to knitting machines and it has for its general object to provide an improved method and improved means relating to the feeding of yarn to the needles of such machines.

A feature of the invention is a method for employment in a knitting machine, of feeding a yarn to the needles which comprises the 10 operation of holding the yarn end, looping the yarn round the hook of one needle and knitting into the work by the aid of other successive needles the loop thus formed and releasing the yarn end during the operation.

Another feature of the invention is the provision in or for a knitting machine, of the combination of a yarn feeder, a trapper associated therewith, and means to move the feeder, while the yarn end remains trapped, 20 in such manner as to wrap the yarn round the hook of that needle which is to be the first to receive the yarn, thereby forming a loop, and subsequently to lead both strands of the loop into the hooks of successive needles, and means to release the trapper during the feeding operation.

A further feature of the invention is the provision, in a knitting machine, of a yarn feeder and mechanism for moving said feeder or to cause it to deliver yarn to a needle which is situated at a position in the needle circle where the needle latch is being closed and the latch has reached approximately a position at right angles to the shank of the needle.

The invention comprises also as a feature the provision, in a knitting machine, of yarn feeder interchanging mechanism comprising a plurality of yarn feeders, which mechanism, to give to the feeders partaking in such change the motion necessary for that purpose, comprises a carrier for all the feeders, means to move in said carrier and relatively thereto the individual feeders concerned in 45 said change, and means to move the carrier.

It is also within the scope of the present invention to provide, in a knitting machine, a yarn-changing mechanism comprising a plurality of yarn feeders, means appropriated to each feeder to impart thereto feed-changing movements, a selector for determining—(when a yarn-change is to be made) 50—which of said feeder-changing means shall be rendered operative, and a pattern device for controlling, at predetermined times in 55 the knitting, the selective effect of said selector.

Other features of the invention will be hereinafter described and specifically pointed out in the appended claims.

A convenient construction according to the present invention is herein described as applied to a knitting machine of the type that is characterized by having superposed needle cylinders within corresponding cam boxes 65 and means to produce relative rotation and rotary reciprocation of the cylinders and cam boxes and by the employment of double-ended needles.

Examples of machines of this type are disclosed in U. S. Patents Nos. 793,791, 70 1,210,866, and British Patent No. 171,483. It is to be understood, however, that the invention is not limited in its application to machines of this particular type as features of the invention are equally applicable to other types of circular or other knitting machines.

A convenient construction of mechanism according to the present invention will now be described with reference to the accompanying drawings, and by way of example, as applied to a circular knitting machine of the type above referred to, the particular machine to which the mechanism is herein considered as applied being one of the aforesaid type in which the cam cylinders are stationary and the needle cylinders rotate.

In the accompanying drawings, all of 80 which are more or less diagrammatic:—

Figure 1 is an elevation of the yarn-changing mechanism showing its position relatively to the needle cylinders of a knitting machine of the type referred to but with 5 some parts omitted.

Figure 2 is a plan of the mechanism shown in Figure 1.

Figure 3 is an elevation looking in the direction of the arrow, Figure 1, of the 10 supporting frame of the mechanism and of the levers for operating the yarn feeders, all the levers being shown in alignment for 75 clearness.

Figure 4 is an elevation partly in section 15 on the line 4—4 of Figure 1 of one of the yarn cutting and trapping devices.

Figure 5 is a section on the line 5—5 of Figure 4 drawn on a larger scale.

Figure 6 is a view showing part of the 20 mechanism for operating one of the cutting and trapping devices.

Figure 7 is a view of the mechanism for operating one of the feeders,

Figure 8 is a section on the line 8—8 of 25 Figure 7 drawn on an enlarged scale,

Figure 9 is a plan of the selector in the position which it occupied during the normal knitting operation,

Figure 10 is a similar view showing the 30 selector in the position which it occupies when a change in the yarn feed is taking place,

Figure 11 is a diagrammatic perspective 35 view illustrating the movement of the yarn feeder in delivering yarn to a needle,

Figure 12 is a fragmentary diagrammatic view showing the needle in side elevation during the delivery of yarn thereto, and

Figure 13 is a diagrammatic perspective 40 view illustrating the movement of the feeder and the position thereof after the yarn has been looped around the needle.

Like reference numerals indicate like 45 parts in the various figures of the drawings.

In this construction there is disposed adjacent the knitting location of the machine, a yarn-feeding mechanism that comprises 50 five independently movable yarn feeders numbered 10—14 respectively, see Figure 1. One of these feeders may be a twin feeder, it having two yarn-guiding passages one to feed a main yarn and the other a plating yarn. Such a twin feeder is illustrated in the copending application of these applicants, Serial No. 196,961, filed June 6, 1927, 55 and it is deemed unnecessary to illustrate this feature in detail. The other feeders are adapted each to feed a single yarn.

During the normal progress of the knitting operation, one of the feeders 10—14 for 60 a predetermined period feeds yarn to the needles while the other feeders are inoperative, at the end of which period the active feeder is withdrawn and its place taken by 65 another feeder, that previously was inac-

tive as far as the knitting is concerned. The length of the time-period during which each feeder is active and the order in which each feeder becomes active during the knitting of a given work-piece is determined by 70 mechanism, presently to be described, that is controlled by the usual pattern chain of the machine. Thus by the aid of this mechanism, a given work-piece may be made up of 75 different portions, one portion composed of yarn derived from one of the said feeders, and another portion composed of yarn derived from another of the feeders, and certain portions of the work-piece if a twin 80 feeder is provided—when the twin feeder is active and both of its passages supplied with yarn—may have a plating yarn incorporated in it.

Each of the feeders 10—14 when regarded in plan—see Figure 2—in which for clearness only the feeders 10 and 11 and their operating levers are shown, consists of a somewhat L-shaped bar or wire whereof one limb 15 termed herein the shank, is mounted to slide endwise and rotate in bearings formed 85 for it in the upright limbs 16, 17 of a U-shaped carrier 18 mounted on a stationary 90 supporting frame 19.

The feeder shanks 15 are disposed horizontally, in the U-shaped carrier 18, one above 95 another in a vertical plane extending approximately parallel with a tangent-plane of the needle cylinders at the yarn-feeding location. The other limb 119 of each feeder is directed toward the needle cylinders, and the feeders are so arranged that the yarn-guiding passages at the ends of the limbs 119 lie adjacent each other in an approximately horizontal plane at or near the usual 100 position which a feeder occupies when feeding yarn to the needles. The U-shaped carrier 18 is pivoted at 20 upon the supporting frame 19 so that it is capable of swinging about a vertical axis located in the neighbourhood of that one of its limbs, namely 17, 105 110 that is the more remote from the yarn passages in the feeders.

From the foregoing it will be appreciated 115 that the yarn-feeding end of each feeder can have imparted to it movements as follows:—A movement tangentially of the needle cylinders by the endwise sliding of the feeder shank 15 in the U-shaped carrier 18: a movement toward and from and substantially radially of said cylinders by the swinging 120 of the U-shaped carrier about its axis 20; and a movement substantially parallel with the axis of said cylinders by a turning of the feeder about the axis of its shank.

In the present construction there are five 125 devices for cutting and trapping the yarn, one of these devices being allocated to each feeder and hereinafter described with reference to Figures 4, 5 and 6. These devices are mounted upon the supporting frame 19 130

in such a position that during the normal knitting operation—i. e. when no feed change is taking place—each is situated adjacent the feeder to which it appertains.

5 In the operation of the machine, when a change of yarn by substitution of one feeder for another feeder is to be made, the feeder to supply the new yarn moves forwardly in the direction of rotation of the needle cylinders—indicated by the arrow in Figure 2—to a point somewhat beyond the normal feed location, namely at the point at which the latches of the descending needles in their closing movement have arrived in a position 10 approximately at right angles to the body of the needles. The said feeder also moves inwardly toward the needle cylinders and its feeding end dips down somewhat to bring it to the level of the latches at this point 15 where it lays its yarn in the needle just above the needle latch—the end of the yarn being at this time trapped by the yarn-trapping device appertaining to this feeder. The latch now closes upon the yarn, the trapping 20 device releases the yarn end which is knitting into the work and the feeder moves upwardly, outwardly and backwardly to its normal position from which it feeds yarn to the needles.

25 30 During these movements of this feeder, the feeder which previously was supplying yarn to the needles moves outwardly and backwardly, and its feeding end dips to place its yarn between the jaws of its cutting and trapping device which thereupon operates to sever the yarn leading to the needles—which knit in the end thus formed—and to trap and hold the yarn going through its feeder to the supply.

35 40 It is to be understood that in the changing of the supply of yarn to the needles, the feeder which is introducing the new yarn lays the yarn, the end of which is at this time trapped, adjacent a descending needle and above the 45 closing latch of this needle which is then standing out approximately at right angles to the needle shank. The combined movement of the descending needle and of the feeder wraps the yarn about the needle hook 50 thereby forming a loop both strands of which are taken up and knitted into the work by the needles succeeding the needle around which the loop was placed initially. The 55 trapper releases its hold on the yarn end either as the yarn is being looped as just described or subsequent to this looping action.

60 The several operations just described are illustrated in Figs. 12, 13, and 14 which are of a purely diagrammatic character and are intended to show only the components of the 65 movements which are imparted to the feeder which is to supply the new yarn when a change of yarn is to be made. The actual path traversed by this feeder will depend upon the timing of the cams whereby its

movements are effected: Figures 11 and 13 are diagrammatic perspective views with the needle cylinder indicated in chain lines at *c*. Let it be assumed that the feeder *f* is to introduce the new yarn. This feeder first moves from its normal inoperative position—in which position the end of the yarn *y* is held in the trapper *t*—forwardly in the direction of rotation of the needle cylinders along the path *p* Figure 11 to a point *p'* somewhat beyond the normal feed location, namely, at the point at which the latches of the descending needles in their closing movement have arrived in a position approximately at right angles to the body of the needles as shown in Figure 12. The feeder *f* also moves inwardly (i. e. substantially radially of the needle cylinder) toward the needle cylinder to the point *p''*, see Figures 11 and 12. The feeding end of the feeder *f* also dips down to a point *p'''* so that it lays the yarn *y* in the needle just above the needle latch *l*. At this time the end of the yarn *y* is held by the trapper *t* appertaining to this feeder *f*. The latch *l* now closes upon the yarn *y* and the trapper *t* releases the yarn end. When the feeder has laid the yarn just above the latch *l* the needle *n* descends to the position shown in Figure 13, and the feeder *f* moves upwardly from *p'''* 70 75 80 85 90 95 100 105 110 115 120 125 130 to *p''*, outwardly from *p''* to *p'*, and backwardly along the path *p⁴*, in Figure 13 to the normal position from which it feeds yarn to the needles. The movement of the feeder from *p'''* to *p''*, then to *p'*, and backwardly along the path *p⁴* combined with that of the descending needle causes the yarn *y* to be wrapped about the needle hook thereby forming a loop *o*, as shown in Figure 13, both strands of which are taken up and knitted into the work by the needles succeeding the needle around which the loop was placed initially.

To produce the dipping or falling and rising movements of the feeding end of each feeder, the shank 15 of each is provided, between the ends of the limbs 16, 17 of the *U*-shaped carrier 18, with a projecting arm 23, see especially Figures 7 and 8, which bears upon a rod 24 carried by the *U*-shaped carrier 18. This rod has two parts of substantially equal diameter and an intermediate portion of lesser diameter, the parts of different diameters being joined by substantially conical portions 25, see Figure 2, constituting cams so that endwise movement of the feeder shank 15 rotates the feeder slightly and moves its feeding end up and down. It will be understood that there are five rods 24, one to each feeder. Conveniently, each projecting arm as shown in Fig. 8 has a split boss 26 and is clamped on the shank 15 by a screw 27.

The mechanism for swinging the *U*-shaped carrier 18 and for moving the feeders 10-14 lengthwise therein is as follows:—On the usual pattern chain 28, see Figure 1, of the

machine, in addition to the usual studs or cam projections thereon, there are located on the side of the chain opposite to that occupied by said studs, other studs 29 especially appropriated to the feed-changing mechanism. These studs which differ relatively in height to correspond to the five feeders are each adapted to engage and operate one arm 30 of an elbow lever pivoted on a horizontal axis 31 in the main frame 32 of the machine, the other arm 33 of which lever is connected by a link 34 with one arm 35 of a second elbow lever, which turns about a vertical axis 36 on the frame 19 and has its other arm 37 engaging in a slot 38 (Figs. 9 and 10) in an endwise movable member 39 which will be hereinafter termed the selector.

This slot is slightly wider than the arm as will be seen on reference to Figures 9 and 20 10 to allow for inaccuracies in the pattern chain. Conveniently, the arm 37 bears against the end of an adjusting screw 138 mounted in the end of the selector 39, and a spring 140 is interposed between said end and 25 the frame 19 to return the selector to its normal position shown in Figure 9. A spring (not shown in the drawings) acting at any suitable point upon the system formed by the bell-crank levers 30, 33 and 35, 37 and 30 their connecting link 34 tends to maintain the arm 30 in the range of the studs 29 on the pattern chain. The selector 39, in the present construction is in the form of a narrow plate or bar mounted in the frame 19 with its longest dimension horizontally disposed. Mounted upon a shaft 40 (Fig. 1) arranged parallel with the longest dimension of the above-mentioned plate is a pawl-carrying frame 41 which is continuously oscillated when the machine is running by an eccentric 42 fast upon 40 a rotating shaft 43 of the machine, the connections between the frame 41 and the disc 42 consisting of a strap 44 connected to one arm 45 of a two-armed lever, the other arm 46 of 45 which is connected by a link 47 to the frame 41.

A set of six pawls (Fig. 2) comprising five pawls 48 and a pawl 148 arranged side by side is mounted upon a shaft 49 supported 50 in the frame 41 and arranged parallel with the shaft 40 upon which that frame oscillates. These pawls, which co-operate, respectively, with five ratchet wheels 50 and a ratchet wheel 150 respectively of six control units 55 hereinafter mentioned, are drag pawls, that is to say each is provided with a hook 51 at its extremity and operates to turn the control unit during the course of its backward stroke. Projecting in advance of its hook each pawl 60 (Fig. 1) has a prolongation 52 arranged to engage on its under side the upper edge 53 of the selector 39 when the pawl arrives near the end of its forward stroke. Approximately opposite each of the five pawls 48, the selector 39 is so shaped as to form a horizontal

shelf 54, see Figures 9 and 10, which is situated at a lower level than the top edge 53 of the selector. This shelf when the selector has been appropriately positioned by an endwise shift, is engaged by the underside of the nose 70 52 of the pawl 48 when said pawl arrives near the end of its forward stroke, and thus maintains the pawl at this time in a position lower than that which it occupies when its nose engages the upper edges 53 of the selector before the shift took place. Adjacent this shelf 54 the selector is cut away as shown at 55, so as to afford no support for the pawl when this cut-away portion is in line with the pawl path. Opposite the pawl 148 appertaining to the control unit which, as presently will be described, is common to all the feeders, the top edge 53 of the selector is cut away as shown at 56 to a level which conveniently may be the same as the shelf 54. This cut-away portion is at the proper times in the operation of the machine, brought by a shift of the selector 39 into line with the path of the pawl 148 to permit it to become operative.

Arranged side by side on the shaft 40 upon which the pawl-carrying frame 41 oscillates are five control units, one appropriate to each feeder, and also another control unit which is common to all the feeders. Each of the former units consists of a ratchet wheel 50 secured to which on one side is a cam 57 (see Figure 7) for operating a feeder and on the other side a cam 58 (see Figure 6) for the cutting and trapping device relating to that feeder. Each ratchet wheel 50 has six teeth, three of which are longer than the others, the long teeth 59 and short teeth 60 alternating.

In the normal operation of the machine, that is to say, when no change in the feed is taking place, the selector 39 is so positioned that the pawls 48 are prevented from engaging their respective ratchet wheels 50. At this time the ratchet wheel 50 appertaining to the feeder 10 which is feeding yarn to the needles has a long tooth 59 in position to be engaged by its pawl when the selector 39 permits it to act, whereas the ratchet wheels appertaining to all the other feeders have a short tooth 60 in this position. In Figure 7 the pawl 48 appertaining to the yarn-feeder 10 is shown at the opposite end of its stroke to that shown in Figure 1.

When a change is to be made in the feed of the yarn, the selector 39 is moved endwise in the direction of the arrow, Figure 10, by the appropriate stud 29 on the pattern chain 28 a distance sufficient to bring one of its cut away portions 55 into line with the pawl 48 of the control unit which is to throw the new feeder into action. This pawl now engages the short tooth 60 which it finds awaiting it and on its backward stroke turns the ratchet wheel 50 and consequently the control unit and actuates the feeder and its as

sociated cutting and trapping device. This same shift of the selector 39 brings its shelves 54 into line with the other four pawls 48, but in the case of three of these pawls the said 5 shelves prevent them from engaging the short ratchet teeth with the result that the pawls make an idle stroke as far as their control units are concerned. The fourth pawl of the four just referred to finds, however, a 10 long tooth 59 awaiting it which notwithstanding that this pawl, like its four companions, rides upon a shelf 54, is still high enough to be engaged by the pawl on its backward stroke so that this control unit is 15 actuated to remove the feeder 10 from feeding position and to actuate its trapping and cutting device.

It will be understood that the cutaway portions 55 of the selector 39 and the 20 shelves 54 thereon are so arranged in relation to the spacing of the five pawls 48 that the selector may be shifted to bring a cutaway portion 55 opposite any one of the pawls and at the same time to place a shelf 25 54 in front of each of the other four pawls, the shelves differing in width to permit this to be effected. Further, a shift of the selector 39 to position a cutaway portion 55 opposite any one of the said five pawls, always 30 brings the cutaway portion 56 opposite the pawl 148 which turns the control unit that is common to all the feeders as this particular unit is required to be operative whenever a feed-change is to be made irrespective of 35 which feeders are to be thrown into and out of action.

To prevent the overthrow of the control units under the action of their pawls a friction device is provided which in the present 40 construction comprises a washer 61 (Fig. 2) located between each two of the control units and a similar washer at each end of the set of these units, the whole being pressed together and against a stop 62 on the shaft 40 by a spiral spring 63 surrounding the shaft and bearing at one end against one end 45 washer 61 and at the other end against an adjusting nut 64 on the shaft. The washers 61 are prevented from turning on the shaft 50 40 by the shaft having a flat 65 formed upon it and the holes in the washers having a complementary shape.

The control unit above referred to as common to all the feeders, comprises a block 66 55 (Fig. 2) which is provided with two arms in which are threaded screws adapted to engage a projection from the ratchet wheel 150 which is located on one side of the block; by adjusting these screws the angular relationship 60 between the block and the said ratchet wheel can be changed to vary the timing of the parts. On the side of the ratchet-wheel 150 opposite to that on which the block 66 is situated is a cam 67 which is secured to 65 said block. This control unit is rotated a

distance equal to one tooth of the ratchet wheel 150 when a change in the supply of yarn to the needles is to be made by means of the pawl 148 which at that time always finds the cutaway portion 56 of the selector in its 70 path so that it is free to turn its ratchet wheel. It will be appreciated that the teeth of the ratchet-wheel 150 are all of the same length. The function of the unit last described is to swing the U-shaped carrier 18 about its pivot 20 to move the feeders 10-14 75 towards and from the needle cylinders 21, 22, and to this end the pivot stud of this carrier is provided with an arm 68 which engages a second arm 69 which swings upon a shaft 70 supported in the frame 19 and is actuated by the cam 67 of the unit. The connection between these two arms is shown in Fig. 3 and consists of a screw 71 threaded in the arm 69 and abutting against the arm 68, a spring 72 (Fig. 1) tending to maintain the arm 68 80 in contact with the screw 71.

By turning this screw the angular position of the U-shaped carrier 18 and therefore the position of the feeders 10-14 radially of the needle cylinders can be adjusted. The free end of the arm 68 projecting from the pivot stud of the U-shaped carrier extends between two adjustable stops 73, 74 on the stationary frame 19, these stops being in the form of screws threaded into upstanding posts one on each side of the lever. The screw 74 limits the inward movement of the feeders towards the needle cylinders so as to prevent engagement to these parts due to overthrow of the feeders while the other screw 73 adjustably limits the movement of the feeders in the opposite direction. The connection between each feeder and the unit especially appertaining to it comprises a lever 75 which abuts against the end of the feeder and has on it a part 76 adapted to engage the cam 57 of the unit. These cam-engaging parts 76 are adjustable for the purpose of varying the position of the feeders lengthwise in the carrier 18. In the construction shown especially in Figure 7 the part 76 is pivoted at 77 to the lever 75 and the position of the part 76 can be adjusted by a screw 78. All five levers 75 of the five units which 90 actuate the feeders individually swing about the shaft 70 that supports the arm 69 which engages the cam 67 of the control unit common to all the feeders. 95

The actual engagement between each lever 75 and the feeder which it operates as shown in the drawings is effected by a screw 79 which screws through a hole in the end of the lever and has on its end a plate 80 which engages the end of the shank 15 of the feeders, the plate 80 being wide enough to allow for movement of the feeder due to the swinging movement of the U-shaped carrier 18 which carries the feeders. Adjustment by the screw 79 obviously varies the lengthwise position of 100 105 110 115 120 125 130

each feeder in the U-shaped carrier 18. It will be appreciated that, if desired, the adjusting screw 79 can be dispensed with and the endwise adjustment of the feeders effected 5 by means of the screw 78 alone. Each of the levers 75 is kept in engagement with its cam by an appropriate spring, for example, a spring such as 81 surrounding the shank 15 of the feeder and bearing at one end against 10 the limb 16 of the U-shaped carrier 18 and at its other end against the projecting arm 23.

Dealing next with the cutting and trapping devices of which there are five, one to each feeder, each device (see especially Figures 4 and 5) comprises a lever 82 having at one end a cutter 83 that slides between two members 84, 85 whereof the member 84 acts as a shear blade to co-operate with the cutter 83 in cutting the yarn and the member 85, 15 positioned at a higher level than the shear blade edge, acts to trap the yarn by nipping it between its side and the non-cutting side of the cutter. The cutting edge of the cutter 83 is formed upon the upper side of a notch 20 formed in the cutter blade into which notch the yarn is placed by the feeder when the yarn is to be cut and trapped. The connection between the cutter-carrying lever 82 of this device and the operating cam 58 of its particu- 25 lar unit consists of a two-armed lever where- 30 of the arm 87 presses against that cam and the other arm 88 has at its upper end a wire 89 which passes through a guiding tube 90 having one end located near the free end of the 35 cutter carrying lever 82 and mounted in the frame 19. For the purpose of adjusting the wire 89 to adjust the height to which the cutter-carrying end of the cutter lever 82 is lifted, the wire is not connected directly to the 40 arm 88 of the cam-operated two-armed lever but the upper end of the arm 88 is slit vertically to receive the wire and the end of the wire has secured to it a nipple 91 which fits within a recess of complementary form 45 formed in the head of a screw 92 which is screwed into the arm 88 and is bored to accommodate the wire.

To permit ready disconnection of the parts the end of the cutter-carrying lever 82 is slit 50 vertically to receive the wire and the end of the wire has secured to it a nipple 93 which fits within a recess of complementary form formed in the upper surface of the lever 82 at the inner end of the slit. The 55 cutting and trapping device is closed by a spring plunger 94 which engages the end of the lever 82 near its point of attachment with the wire 89. In the particular construction now being described, the body parts of the 60 devices are mounted side by side on two pins 95 projecting from a stationary part 96 of the machine, holes being formed in these parts to receive the pins which are provided with nuts to secure the parts in place the devices being 65 spaced apart by any suitable means. The cut-

ter-carrying levers 82 of these devices are also mounted upon a pivot 97 common to all of them and formed by a stud screwed into the stationary part of the machine. Each of the cams 58 for these devices is provided with 70 six cam projections 100 which engage a projection 101 on the arm 87 of the corresponding two-armed lever hereinbefore referred to. When the cam projections 100 are operative, the cutter and trapping devices are open 75 as shown in Figures 4 and 5, but when the cam projection 100 leaves the projection 101 the spring-controlled plunger 94 causes the lever 82 to turn about its pivot 97 and the yarn which has then been introduced into the de- 80 vice to be first trapped and then cut.

The non-rotating shaft 40 which supports the six control units before mentioned and upon which the pawl-carrying frame 41 oscillates is supported at its ends at the bottoms of two downwardly-inclined slots 98 formed in the frame 19 in which position it is secured in place by a screw 99 passing through a diametral hole in each of its ends and screwing into the frame 19. This manner of supporting these parts is advantageous in that it enables the shaft and all the parts it carries to be removed readily from the machine for purposes of inspection or adjustment when the link 47 is disconnected from 85 the frame 41.

It is to be understood that the invention is not restricted to the precise constructional details described, as various changes may be made therein, for example in order to suit 100 the particular machine to which the invention is applied, or the number of yarn changes which are required.

We claim:

1. In a knitting machine having a series of 105 needles, the combination with a yarn feeder, of a trapper associated therewith having a yarn end trapped therein, mechanism for moving the feeder while the yarn end remains trapped so as to loop the yarn about a needle 110 and to feed both strands of the loop to successive needles, and means to release the yarn from the trapper.

2. In a circular knitting machine having 115 a series of needles provided with hooks and latches for said hooks, the combination with a yarn feeder, of a trapper associated therewith having a yarn end trapped therein, mechanism for moving the feeder while the yarn end remains trapped so as to loop the 120 yarn about the hook of a needle which is situated at a position in the needle circle where the needle latch is closing and extends approximately at right angles to the needle, and for thereafter moving the feeder to feed both strands of the loop to successive needle hooks, and means to release the yarn from the trapper.

3. In a knitting machine having a series 125 of needles, the combination with a plurality

- of yarn feeders, of trappers associated respectively with the feeders, mechanism for selecting and moving a feeder while the yarn end associated therewith is trapped by the 5 corresponding trapper so as to loop the yarn about a needle and to feed both strands of the loop to successive needles, said mechanism including a movable carrier in which all of said feeders are supported for movement 10 relatively thereto, means for moving said carrier and for moving the selected feeder relatively to said carrier, and means to release the yarn from the trapper.
4. In a knitting machine having a series of 15 needles, the combination with a plurality of yarn feeders, of mechanism for substituting the yarn guided by one feeder for the yarn guided by another feeder and being delivered to the needles, said mechanism including a 20 plurality of trappers associated respectively with the feeders, the trapper associated with said first named feeder holding the free end of the yarn to be substituted, means for moving said first named feeder so as to loop the 25 yarn about a needle and feed both strands of the loop to successive needles, means to release the yarn end from the trapper, means to move said second named feeder to deliver the replaced yarn to the trapper associated therewith, and means for severing the replaced yarn.
5. In a knitting machine having a series of needles, a yarn-changing mechanism comprising a plurality of relatively movable yarn 30 feeders, a common carrier for said feeders in which said feeders are movably supported, and means for moving said carrier for simultaneously moving said feeders and for moving said feeders individually with respect to 35 said carrier to impart yarn-changing movement to said feeders.
6. In a knitting machine having a series of needles, a yarn-changing mechanism comprising a plurality of relatively movable 40 yarn feeders, a common carrier for said feeders in which said feeders are movably supported, said carrier being movable to shift said feeders toward and away from said needles, and said feeders being movable within 45 said carrier in directions substantially transverse to and longitudinally of said needles, and means for moving said carrier and selecting and moving individual feeders to impart 50 yarn-changing movement to said feeders.
- 55 7. In a knitting machine, yarn feeder interchanging mechanism comprising a U-shaped pivotally mounted carrier, a plurality of substantially L-shaped yarn feeders whereof one limb of each feeder is mounted 60 to slide endwise and to rotate in the side limbs of the carrier, means to turn said carrier about its pivot, means to move each feeder endwise, and means to rotate each feeder about the axis of its aforesaid limb, for the 65 purpose set forth.
8. In a knitting machine, yarn feeder interchanging mechanism comprising a movable carrier, a plurality of yarn feeders mounted for individual rotary and bodily shifting movements in said carrier, cam means fixedly mounted on said carrier and engaged by said feeders and acting to rotate the latter when the feeders are shifted bodily, and means for shifting the feeders and moving said carrier to impart yarn-changing movements thereto.
9. In a knitting machine, the combination with a plurality of yarn feeders, of mechanism for imparting yarn-changing movements to said feeders, said mechanism including a plurality of pawl and ratchet devices, one associated with each feeder, each pawl being normally disengaged from the corresponding ratchet, means for continuously reciprocating said pawls, and selector mechanism for shifting certain of said pawls into operative engagement with the corresponding ratchets to impart yarn-changing movements to the associated feeders.
10. In a knitting machine, the combination with a plurality of yarn feeders, of mechanism for imparting yarn-changing movements to two of said feeders to substitute one for the other, said movements having a component common to both feeders, said mechanism including a plurality of normally inoperative devices, each associated with a single feeder, for imparting individual movement thereto, and normally inoperative means associated with all of said feeders for imparting simultaneous movement thereto, and selector mechanism operable to select and set in operation two of said devices and said means to impart movement to the corresponding pair of feeders.
11. The combination set forth in claim 10 in which the said devices and the said means each include a normally disengaged pawl and ratchet mechanism, and means for continuously reciprocating said pawls, said selector mechanism acting to operatively engage the pawl and ratchet mechanisms of the corresponding devices and means selected thereby.
12. In a knitting machine, the combination with a plurality of yarn feeders, of mechanism for imparting yarn-changing movements to said feeders, said mechanism including a plurality of pawl and ratchet devices, one associated with each feeder, an element positioned adjacent said ratchets and normally preventing contact between said pawls and ratchets, said element being provided with slots to receive said pawls to permit the latter to engage with the corresponding ratchets, said slots being so positioned with respect to said pawls that the extent movement of said element transversely of said pawls permits certain of said pawls to fall in said slots to effect selection of the pawl and ratchet devices, means for reciprocating

said pawls, and a selector mechanism for moving said element to a predetermined extent.

13. In a knitting machine, the combination with a plurality of yarn feeders, of a plurality of trappers each associated with one of said feeders, a series of separate control means each connected with a single feeder and associated trapper to cause the latter to execute yarn-changing movements, and selector mechanism for selecting certain of said control means to cause the latter to actuate the associated feeder and trapper.

In testimony whereof we have signed our names to this specification.

PERCIVAL ARTHUR BENTLEY.
